WATER SKI LAUNCHING CARRIAGE

George P. Block, Troy, N. Y.

Application October 26, 1951, Serial No. 253,379

3 Claims. (Cl. 104—53)

1

The present invention relates to new and useful improvements in water-ski launching devices to facilitate the starting motion of the skier from a stationary position. The invention is designed primarily for use in teaching the art of water skiing and to enable the skier to be towed by a boat from a stationary position without danger of the skier losing his balance and to enable a boat with only sufficient power to plane a skier to start the skier with a minimum of resistance.

Accordingly it is an important object of the present invention to provide a carriage adapted to travel on tracks leading from the shore or other supporting structure into the water and on which the skier is seated in a position to be towed by a boat and pulled free of the carriage as the required planing momentum is obtained.

Another object of the invention is to provide adjustable means for the seat on the carriage as well as adjustable means for the track or rail on which the carriage travels to compensate for variations in the water level due to tide changes, or other reasons.

A still further object is to provide a device of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, references being had to the accompanying drawings forming part hereof, wherein like numerals refer to like parts throughout, and in which:

Figure 1 is a perspective view; and

Figure 2 is a transverse sectional view taken on the line 2—2 of Figure 1.

Referring now to the drawing in detail, wherein for the purpose of illustration I have disclosed a preferred embodiment of my invention, the numerals 5 and 6 designate a pair of tracks which may be constructed of inexpensive material, such as wooden planks and supported at their rear ends on blocks or other suitable foundations 7 on the shore of a body of water and supported at their front ends on posts 8 placed in the water outwardly from the shore. The posts 8 may be attached to a portable base or frame structure 9 for removal from the water as a unit, when not in use.

The front end of the tracks 5 and 6 are vertically adjustable on the post 8 by means of legs 10 which are suitably connected at their upper ends to the front ends of the tracks and pro-

vided with a row of vertically spaced apart openings 11 to selectively receive a pin 12 carried by the post 8 to secure the legs in vertically adjusted position and thus to raise or lower the front end of the tracks 5 and 6 to compensate for the rising and falling of the tide, or other water level variations.

A carriage 13 preferably of a rectangular frame construction is provided at its underside with rollers or wheels 14 at the side edges of the carriage for traveling on the tracks 5 and 6. Guide flanges 15 are suitably secured to the underside of the carriage to travel along the inside of the rails 5 and 6 to keep the rollers 14 on the track. A seat 16 is secured to the front edge of the carriage 13 and a rope or other flexible member 17 connects the rear edge of the carriage to a stake 18 on the shore to check the forward movement of the carriage and by means of which the carriage may be pulled rearwardly along the track to a starting position.

The seat 16 is provided with vertically adjustable legs 19 which are slideable vertically in brackets 20 secured to the carriage and the legs are formed with vertically spaced apart openings 21 to selectively receive a pin 22 carried by the bracket to secure the legs and the seat in vertically adjusted position relative to the carriage.

An endless rope or cable 23 is trained around pulleys 24 attached to front and rear stakes 25 and 26 positioned respectively outwardly in the water and on the shore and a hook 27 is attached to the lower flight of the endless rope.

In the operation of the device the carriage 13 is pulled to its rearward position on tracks 5 and 6 and a handle 28 of the tow rope 29 to be pulled by a boat 30 is engaged with the hook 27 and the rope 23 pulled on the pulleys 24 to bring the handle 28 within reach of a person occupying the seat 16. As the boat 30 moves outwardly from the shore the tow rope 29 is held by the skier in the normal manner and the skier's weight on the carriage 13 causes it to move outwardly on the tracks 5 and 6 and enables the skier occupying the seat to balance himself on the skis while in a seated position and before subjecting his weight to the ski. The forward movement of the carriage 13 is checked by the rope 17 while the skier continues his forward travel in a normal planing position on the skis.

Both the seat 16 and the tracks 5 and 6 may be adjusted vertically to compensate for the rise and fall in the tide or other water level variations so that the skis will rest on the surface of the water while the skier occupies the seat.

In view of the foregoing description taken in conjunction with the accompanying drawings, it is believed that a clear understanding of the device will be quite apparent to those skilled in the art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention, what is claimed as new is:

1. A water ski launching apparatus comprising a trackway, a carriage mounted to travel on the trackway, and a seat on the carriage adapted to be occupied by a skier in a position to be towed away from the carriage, said seat being disposed above the surface of the water a height sufficient to enable the feet of a skier seated thereon to touch the water, said trackway being open substantially throughout its length to provide a clear and unobstructed path for the carriage along the track.

2. A water ski launching apparatus comprising a pair of tracks having at least one end supported

10

over a body of water, a carriage mounted to travel on the tracks, and a seat on the carriage adapted to be occupied by a skier in a position to be towed away from the carriage, said tracks being spaced from one another throughout their length to provide an open space therebetween for a clear and unobstructed passage of the carriage along the track, said seat being disposed above the surface of the water a height sufficient to enable the feet of a skier thereon to touch the water.

3. A water ski launching apparatus comprising a pair of tracks having at least one end supported over a body of water, a carriage mounted to travel on the tracks, means checking forward movement of the carriage, said tracks being spaced from one another throughout their length to provide an open space therebetween for a clear and unobstructed passage of the carriage along the track, said carriage being disposed above the surface of the water a height sufficient to enable the feet of a skier thereon to touch the water.
